Primary Examiner — L. A. Grabenstetter*Assistant Examiner* — Danielle Nichole Bowly(74) *Attorney, Agent, or Firm* — Cooper Legal Group, LLC(57) **CLAIM**

The ornamental design for a roll core for labels, as shown and described.

DESCRIPTION

- 1.1: Perspective
- 1.2: Perspective
- 1.3: Front
- 1.4: Back
- 1.5: Top
- 1.6: Bottom
- 1.7: Left
- 1.8: Right
- 2.1: Perspective
- 2.2: Perspective
- 2.3: Front
- 2.4: Back
- 2.5: Top
- 2.6: Bottom
- 2.7: Left
- 2.8: Right

The broken lines represent environmental subject matter, namely a roll of labels surrounding the roll core for labels, and form no part of the claimed design.

1 Claim, 16 Drawing Sheets(56)
